JAMES HENRY BRADFORD, OF WESTBOROUGH, MASSACHUSETTS.

Letters Patent No. 83,912, dated November 10, 1868.

STENCIL-PLATE FOR NUMBERING BARRELS, &c.

The Schedule referred to in these Letters Patent and making part of the same.

Be it known that I, JAMES HENRY BRADFORD, of the town of Westborough, county of Worcester, and State of Massachusetts, have invented certain new and useful Devices for Increasing the Facility and Rapidity of Marking and Numbering Barrels, Boxes, and Packages of Goods, for directing or describing the same, and I hereby declare the following to be a full and sufficient description thereof, reference being had to the accompanying drawings, and references thereon, in which—

Figure 1 represents the compound stencil-plate, folded or slid together, one piece upon the other, like a tablet of ivory cards or diary-plates, and connected together by a centre-pin or eyelet, on which, as a centre, they are turned.

Figure 2 represents the pack or tablet closed, the outside or top plate A turned on its centre-pin to the extreme left of the figure, revealing the three concentric rows or curves, each containing the nine digits and a cipher, to be explained herein below.

Figure 3 represents the whole group of plates, four in number, extended or opened out, on their centre-pin, equidistant from each other, each occupying the quadrant of a circle.

The nature of the invention consists in the arrangement and combination of a number of stencil-plates, to form a compound plate, by which any number or series of numbers may be marked in right lines, whether horizontal, oblique, or vertical.

The arrangement seen in the present case provides for the three rows of figures, which may number from 1 to 999, inclusive. It is a compound plate, composed of four single plates, connected by a common centre-pin, E, which passes through each plate, and on which the plate may be turned at will, as appears by inspecting fig. 3.

The top plate A is the shield or cover for those on

which it rests, and contains three openings, A¹ A² A³, which represent the three curved concentric lines of figures. A¹ represents the inner curved line, A² the first and second together, and A³ the outer line, including the second and the first, to be read as three figures side by side. Through the first is read a single figure only; through the second, two figures, or unit and ten; and through the third, three figures, or a unit, ten, and hundred's place. It is this combination and arrangement of several concentric curved lines of figures, to form an arrangement of figures in right lines, covering two or more places of figures, as shown in the drawings, and described in the specification, that constitute the gist of the invention.

From what has been said, it is obvious, from inspecting figs. 2 and 3, that the sections B, C, and D, turning on centre-pin E, may be so rotated as to represent, in a horizontal line, any number, from 1 to 999 inclusive, by merely sliding these curved lines of figures on each other. Thus, using fig. 2, suppose we wish to mark, on a box, 159. Looking on fig. 2, we find 555 on the middle line. Bring up the outer curve till its figure 9 is opposite the 5, and bring down the inner curve till its figure 1 is opposite the figure 5 of the middle curve, and we have the figures sought. Now rotate the shield A till opening A³ is brought exactly over the figures 159, apply the marking-brush to the stencil-plate, and the work is done.

What I claim as my invention, and desire to secure by patent, is—

The combination of two or more concentric curves of the nine digits, for marking numbers in horizontal or other right lines, substantially as described.

JAMES HENRY BRADFORD.
